United States Patent

Des. 234,918
Patented Apr. 15, 1975

234,918

STORAGE CONTAINER

Norman O. Sauey, Jr., and Robert C. Hazzard, Portage, Wis., assignors to Portage Industries Corporation, Portage, Wis.

Filed Feb. 26, 1973, Ser. No. 336,074

Term of patent 14 years

Int. Cl. D9—03

U.S. Cl. D9—219

FIG. 1 is a side elevation view of a storage container showing our new design;

FIG. 2 is a top plan view;

FIG. 3 is a bottom plan view; and

FIG. 4 is a sectional view taken along line 4-4 of FIG. 2.

We claim:

The ornamental design for a storage container, as shown.
